JACOB E. NEAHR, OF NEW YORK, N. Y.

MATCH-IGNITING DEVICE.

1,194,867.

Specification of Letters Patent. Patented Aug. 15, 1916.

Application filed October 20, 1914. Serial No. 867,598.

To all whom it may concern:

Be it known that I, JACOB E. NEAHR, a citizen of the United States, residing in the city, county, and State of New York, have 5 invented certain new and useful Improvements in Match-Igniting Devices, of which the following is a specification.

This invention relates principally to a combined match-safe and match-igniter, and 10 it is especially adapted for pocket use, although certain features may be used in either match-safes or match-igniters considered separately, and whether adapted for pocket use or not. 15 One of the main objects of the invention is to provide a simple, inexpensive and durable structure, sufficiently compact to be adapted for pocket use, and containing safely a supply of matches and means for 20 igniting them.

The invention, which may be carried out in a variety of ways, is illustrated, by way of example, in the form of a tube closed at both ends; pressure upon one of the ends 25 serving to cause the protrusion, from the other end of the tube, of a match-igniter, followed by a match-box, so that a match may readily be withdrawn from the box and ignited; whereupon the box and igniter may 30 be pressed back telescopically into the tube, closing the same; both the matches and the igniter being protected against injury, while the pocket of the user does not come in contact with the material of the match-heads or 35 of the igniter.

The match-box fits telescopically within the tube or casing, and carries upon its upper end the match-igniter, which is preferably in the form of an ignition-strip wound 40 upon a drum. The drum is secured upon the top of the match-box, which thus serves as a means whereby the igniter is supported upon the casing, which latter serves as a convenient handle by which to hold the device when striking a match. The ignition-strip is coiled within the drum, and paid out and applied upon the periphery of the drum as required; the ends of the applied portion of the strip being clipped to the drum. 45 The clip may be readily opened to release the strip, and then closed after adjustment of the strip; the drum and the clip in its closed condition being adapted to slip within the casing or tube. The match-box has 50 an open side, the opening being of such form that the mere tipping of the device will

cause the matches to hang out of the box but without likelihood of dropping therefrom, so that it is very easy to select a match and withdraw it, and there is no need to insert the fingers in the box for the purpose of securing a match, and hence the box may be quite small, as is desired for pocket use. 60

Other features and advantages will hereinafter appear.

In the accompanying drawings, Figure 1 is a perspective of the cover of the ignition-strip drum, the cover being removable to give access to the interior. This cover moreover normally closes one end of the 70 main casing or tube. Fig. 2 is a perspective of the open-sided match-box, withdrawn from the casing and showing the ignition-strip drum mounted thereon. Fig. 3 is a perspective view of the casing, which may 75 be a simple open-ended tube. Fig. 4 is a central sectional elevation of the device in closed condition, and illustrating the manner of opening the same by pressing the finger upon one end thereof. Fig. 5 is an 80 enlarged perspective to illustrate the manner of clipping the ends of the applied portion of the ignition-strip upon the drum. Fig. 6 is a plan of the parts seen at Fig. 2. Fig. 7 is a plan to illustrate the method of 85 adjusting the ignition-strip upon the drum. Fig. 8 shows in enlarged section the upper portion of the device in closed condition. Fig. 9 illustrates the device opened up and tipped to cause the matches to hang out 90 therefrom for accessibility. Fig. 10 shows in perspective separately the parts that make up the Fig. 2 structure.

The matches 1 are contained in a box 2, which telescopes within a tubular holder 3 95 serving as a handle; the bottom 4 of the box serving to close the lower end of the tube, and also serving as a finger-piece whereby to push the box out from the other end of the tube. The latter is preferably lined with 100 paper or suitable material 5, which aids in frictionally holding the casing and box in different relative positions, and also tends to keep the box clean and bright.

The side of the box is open at 6, for insertion and withdrawal of matches; the opening being preferably in the form of an elongated V-shape cut, terminating at its small end between the top and bottom of the box. By tipping the box as at Fig. 9, the matches 110 are caused to hang out of the opening, where they are readily accessible and can

easily be withdrawn one by one, without likelihood of any match falling out of the box. The V-shape cut terminates so far above the bottom of the box, that the 5 matches are supported between their ends, so as not to fall out at Fig. 9. The cut 6, however, may be of other form, so long as it terminates at a sufficient height for this purpose. The top and bottom of the box 10 may be near enough to each other to confine the matches against liability of jumping out of the opening 6.

The match-igniter, carried upon the upper end of the match-box 2, comprises a drum 7, 15 to contain a coil of match-ignition strip 8, one end whereof is pulled out through an eye 9 in the wall of the drum and applied to the periphery of the drum by winding thereon, as at 10. The ends of the applied 20 portion of the strip are secured by a clip 11, projecting up from an arm 12, pivoted at 13 to the drum bottom. The clip may have converging sides to be sprung between the edges of the eye 9, to hold the strip securely 25 at said eye; and the arm 12 may be pressed firmly against the bottom of the drum, to make sufficient friction to hold the clip securely in strip-clamping or closed position. Normally the clip must be closed as at Fig. 30 6, in order to permit the match-igniter to slip into the casing 3; the arm when open forming an obstruction to the closing of the ignition device into the tube, since at that time the arm projects beyond the contour 35 of the casing, as at Fig. 7. The drum, although made of such diminutive proportions as to slip within a casing 3 of say three-fourths of an inch in diameter, is still of ample size to serve the purpose, and also 40 may accommodate a coil of sufficient length to last for months or years with ordinary usage.

The coil may surround a central stud (or core) 14, rising from the bottom of the 45 drum; and the drum may be covered by a disk 15, having a threaded shank 16 to screw into said stud; said disk normally serving to close the upper end of the casing, Figs. 4, 8.

The means whereby the drum is supported 50 upon the match-box 2, may comprise a disk 17 whereby the box is headed, and to which the bottom of the drum is secured by a rivet 18. The circular edge of the box may fit 55 into a rabbet 19 cut on the lower edge of the disk. The clip arm 11 may work in a recess or seat 20 cut in the upper face of the heading disk 17. The latter may have a circular brim or flange 21 within which the drum 60 fits; said flange 21 serving as a bottom flange for the drum, and coöoperating with the top flange of the drum (consisting of the overhanging edge of the cover 15) to confine the ignition strip against lateral displacement.

65 The outward movement of the match-box

from the tube or casing may be limited by an interior stop 22, which will engage (Fig. 9) the bottom of the V-shape notch in the box for this purpose. Said stop may also serve to limit the closing movement of the 70 device, by engaging (Fig. 8) with the under side of the cover 15 of the strip drum. Upon removing the cover, the box may be thrust out of the bottom of the casing and withdrawn; the bottom of the flange 21 being cut away at 23 to afford a clearance 75 for the stop 22 when the box and drum are to be taken out of the casing.

Variations may be resorted to within the scope of the invention, and portions of the 80 improvements may be used without others.

Having thus described my invention, I claim:

1. A match-safe comprising a match-ignition device comprising a coil, and a casing 85 to contain said match-ignition device and the matches; said match-ignition device mounted for a movement to expose the same for striking a match thereon; means being connected with said match-ignition device 90 to be effective at the movement thereof, for rendering the incased matches accessible when the match-ignition device is exposed, and inaccessible when the match-ignition device is returned within the casing. 95

2. The combination of an incasing structure within which matches may be inaccessible confined; a match-ignition device comprising a coil normally inaccessible in said incasing structure; and means supporting 100 said match-ignition device upon said incasing structure in a manner to permit movement of the match-ignition device away from the incasing structure and simultaneously cause the matches in the incasing 105 structure to be rendered accessible.

3. A combined match-safe and ignition-device, comprising a drum or magazine portion upon which an ignition-strip is applied and within which the strip is stored, and a 110 match-containing handle portion forming a casing within which said drum with its strip is confined; means movable relatively to said casing being provided for rendering the matches accessible and for exposing the ignition strip to permit the striking of a match 115 thereon.

4. A combined match-safe and ignition-device, comprising a drum or magazine upon 120 which an ignition-strip is applied and within which the strip is stored, a match-holding box, a casing structure, and means connecting said drum and said match-holding box for simultaneous movement relatively to said casing structure, to render the matches accessible and expose the drum and ignition-strip to permit striking a match thereon. 125

5. The combination of an open-ended tube or casing; an open-sided match-box having a bottom and fitting in said casing, said bot- 130

5 tom closing the lower end of said tube and affording means for thrusting the box at will out from the top of the tube; and a magazine or drum mounted upon the upper end of said match-box within said tube, and comprising a portion which closes the upper end of said tube; a strip of match-igniting material being applied upon said drum.

10 6. The combination of an open-ended tube or casing; an open-sided match-box having a bottom and fitting in said casing, said bottom closing the lower end of said tube and affording means for thrusting the box at will out from the top of the tube; a magazine or 15 drum mounted upon the upper end of said match-box within said tube, and comprising a portion which closes the upper end of said tube; a strip of match-igniting material being applied upon said drum, and extending 20 within the drum; and means releasably securing the applied strip upon the exterior of the drum.

25 7. The combination of an open-ended tube or casing; an open-sided match-box having a bottom and fitting in said casing, said bottom closing the lower end of said tube and affording means for thrusting the box at will out from the top of the tube; a magazine or drum mounted upon the upper end of said 30 match-box within said tube, and comprising a portion which closes the upper end of said tube; a strip of match-igniting material being applied upon said drum; and means to prevent the box from being extruded from 35 the bottom of the tube.

40 8. A pocket ignition-device, comprising a magazine or drum portion upon which an ignition-strip is applied and within which the strip is coiled, and a handle portion within which said drum and strip are incased; said drum with the strip being movable out of the handle portion, to expose the applied portion of the strip for striking a match thereon.

45 9. A pocket-safe comprising a handle portion, and a match-ignition device comprising a coil of match-ignition strip incased within said handle portion and mounted for a movement to expose the same for striking a match thereon; said match-ignition device comprising a support for the coil of match-ignition strip.

50 10. A pocket ignition-device, comprising a casing, and a magazine or drum within said casing; a coil of match-ignition strip being partly wound upon said drum, and the latter being mounted for movement out of the casing to expose the strip for striking a match thereon; means being provided for 55 affording a support or connection to retain the drum upon the casing when the drum is moved to strip-exposing position.

60 11. A pocket ignition-device, comprising a tubular casing; a magazine or drum within said casing; a coil of match-igniting strip

being partly wound upon said drum; the drum mounted for a movement of protrusion from the casing; the strip extending within the drum, and the latter having an eye through which the strip may be withdrawn from the drum; and a clip mounted on the drum to clip the strip to the drum at said eye; said clip when open forming an obstruction to the return of the drum within the casing, but being mounted to fold to 75 the drum to permit the latter to be returned within the casing.

12. A pocket ignition-device, comprising a magazine or drum to the circumference of which an ignition-strip is applied; a portion 80 of the strip extending within the drum; a casing for normally confining said drum with its applied strip; and means whereby said drum is supported upon said casing to permit the movement of the drum out of the 85 casing in a manner to expose the strip for the entire circumference of the drum.

13. A pocket ignition-device, comprising a magazine or drum portion upon which an ignition-strip is applied and within which 90 the strip is coiled, a handle portion within which said drum and strip are incased; said drum with the strip being movable out of the handle portion, to expose the applied portion of the strip for striking a match 95 thereon, and a match-containing box confined within said handle portion and movable with said drum out of said handle portion.

14. A pocket ignition-device, comprising 100 a magazine or drum portion upon which an ignition-strip is applied and within which the strip is coiled, a handle portion within which said drum and strip are incased; said drum with the strip being movable out of 105 the handle portion, to expose the applied portion of the strip for striking a match thereon, and a match-containing box confined within said handle portion and movable with said drum out of said handle portion; said 110 box forming means, whereby the exposed drum is supported upon said handle portion.

15. A pocket ignition-device, comprising a magazine or drum portion upon which an ignition-strip is applied and within which 115 the strip is coiled, a handle portion within which said drum and strip are incased; said drum with the strip being movable out of the handle portion, to expose the applied portion of the strip for striking a match 120 thereon, and a match-containing box confined within said handle portion and movable with said drum out of said handle portion; said box forming means, whereby the exposed drum is supported upon said handle 125 portion, and having a bottom normally closing the casing and serving as a finger-piece for thrusting the drum out of the casing.

16. The combination with a coil of ignition-strip, and an ignition-strip-containing 130

- drum or magazine upon which a portion of the strip is releasably applied, of a match-containing box connected to said drum, and means normally constituting a safe for said drum and box but capable of movement relatively to the drum and box to render the matches accessible and expose the strip for striking a match thereon.
17. A pocket-safe comprising a handle portion, a match-ignition device comprising a coil of match-ignition strip incased within said handle portion, and a support for said match-ignition device; said support telescoped within said handle portion and movable to expose the match-ignition device for striking a match thereon.
18. A pocket-safe comprising a handle portion, a match-ignition device comprising a coil of match-ignition strip incased within said handle portion and a support for said match-ignition device; said support telescoped within said handle portion and movable to expose the match-ignition device for striking a match thereon, and having a bottom and an open side, to constitute a match-box which is opened by thrusting the same out from the handle and closed by shutting the same within the handle.
19. The combination of a tubular casing; a match-container telescoped within the casing; a magazine or drum connected to said match-container and also confined within the casing to be extruded therefrom with said match-container; an ignition-strip applied upon the surface of the drum and extending within the drum; said drum having an eye for the passage of the strip; and a releasable clip for holding the applied strip upon the drum; said clip mounted upon the drum and normally confined within said tubular casing.
20. The combination of a tubular casing; a match-container telescoped within the casing; a magazine or drum connected to said match-container and also confined within the casing to be extruded therefrom with said match-container; and an ignition-strip applied upon the surface of the drum and extending within the drum; said drum having an eye for the passage of the strip; said drum having flanges between which the strip is confined, and said flanges approximately fitting the interior of said tubular casing.
21. The combination of a tube, and a combined match-box and ignition device confined telescopically within said tube and having portions which close the ends of the tube, one of said closing portions being exposed to serve as a finger-piece, pressure upon which may expose the igniter and match-box at the other end of the tube.
22. The combination of an open-ended tube or casing; an open-sided match-box having a bottom and fitting in said casing,
- said bottom closing the lower end of said tube and affording means for thrusting the box at will out from the top of the tube; and a magazine or drum mounted upon the upper end of said match-box within said tube, and comprising a portion which closes the upper end of said tube; a strip of match-igniting material being applied upon said drum; said tube lined with paper or the like, to afford frictional resistance to the telescopic movement of the box, and tend to clean or polish the latter.
23. The combination of a tube or casing; an open-sided match-box telescoped within said casing and closing one end thereof; a disk or device whereby said match-box is headed; an ignition-strip drum fastened upon said disk; and a cover for said drum; said cover normally closing the upper end of said tube.
24. The combination of a tube or casing; an open-sided match-box telescoped within said casing and closing one end thereof; a disk or device whereby said match-box is headed; an ignition-strip drum fastened upon said disk; a cover for said drum; said cover normally closing the upper end of said tube; an arm confined between said disk and said drum; and a clip upon said arm to clip an ignition-strip applied upon said drum.
25. The combination of a tube or casing; an open-sided match-box telescoped within said casing and closing one end thereof; a disk or device whereby said match-box is headed; an ignition-strip drum fastened upon said disk; a cover for said drum; said cover normally closing the upper end of said tube; said disk having a flange within which said drum is fitted; and an ignition-strip applied upon the face of said drum and clipped thereto; the edge of said cover forming an upper flange for said drum; and said strip being confined against lateral displacement by means of said flanges.
26. The combination of a tube or casing; an open-sided match-box telescoped within said casing and closing one end thereof; a disk or device whereby said match-box is headed; an ignition-strip drum fastened upon said disk; and a cover for said drum; said cover normally closing the upper end of said tube; a stop being provided in said tube to limit the outward telescopic movement of said box, and to engage said cover to limit the closing movement thereof.
27. The combination of a tube or casing; an open-sided match-box telescoped within said casing and closing one end thereof; a disk or device whereby said match-box is headed; an ignition-strip drum fastened upon said disk; and a cover for said drum; said cover normally closing the upper end of said tube; a stop being provided in said tube to limit the outward telescopic move-

ment of said box, and to engage said cover to limit the closing movement thereof; said cover being removable to permit the box to be thrust out from the lower end of the tube and removed therefrom.

28. The combination of a tube or casing; an open-sided match-box telescoped within said casing and closing one end thereof; a disk or device whereby said match-box is headed; an ignition-strip drum fastened upon said disk; a cover for said drum; said cover normally closing the upper end of said tube; a stop being provided in said tube to limit the outward telescopic movement of said box, and to engage said cover to limit

the closing movement thereof; said cover being removable to permit the box to be thrust out from the lower end of the tube and removed therefrom; an ignition-strip coil confined in said drum by said cover; 20 said drum having an eye through which the strip is led out, the outer portion of said strip being applied upon said drum; and a clip upon said drum to hold the applied portion of the strip upon the periphery of 25 the drum.
